UNITED STATES PATENT OFFICE.

WILLIAM W. NEÜER, OF WILKESBARRE, PENNSYLVANIA.

DESIGN FOR REED-ORGAN CASES.

Specification forming part of Design No. **7,835**, dated November 3, 1874; application filed September 30, 1874.
[Term of Patent 3½ years.]

To all whom it may concern:

Be it known that I, WILLIAM WASHINGTON NEÜER, of the city of Wilkesbarre, in the county of Luzerne and State of Pennsylvania, have invented a Design for Cases of Reed-Organs, of which the following is a specification:

The nature of my design is fully represented in the accompanying photographic illustration,

to which reference is made. Said photographic illustration is marked No. 4.

What I claim as my invention is—

The design for an organ-case, as represented in the accompanying photographic illustration.

WILLIAM WASHINGTON NEÜER.
